CLAIM

The ornamental design for a barbecue grill, as shown and described.

DESCRIPTION

FIG. 1 is a rear side perspective view of a closed embodiment of barbecue grill.

FIG. 2 is a right side view of the embodiment of FIG. 1 of barbecue grill.

FIG. 3 is a top view of the embodiment of FIG. 1 of barbecue grill.

FIG. 4 is a bottom view of the embodiment of FIG. 1 of barbecue grill.

FIG. 5 is a rear view of the embodiment of FIG. 1 of barbecue grill.

FIG. 6 is a left side view of the embodiment of FIG. 1 of barbecue grill; and,

FIG. 7 is a front view of the embodiment of FIG. 1 of barbecue grill.

The broken lines in the figures depict environment and form no part of the claimed design.
